UNITED STATES PATENT OFFICE.

WILLIAM DAVIS SMITH, OF CYNWYD, PENNSYLVANIA.

WHEELED TOY.

1,207,648.

Specification of Letters Patent.

Patented Dec. 5, 1916.

Application filed July 14, 1916. Serial No. 109,334.

To all whom it may concern:

Be it known that I, WILLIAM D. SMITH, a citizen of the United States, residing at Cynwyd, in the county of Montgomery and 5 State of Pennsylvania, have invented new and useful Improvements in Wheeled Toys, of which the following is a specification.

This invention relates to wheeled toys, particularly to toys of the trundle-wheel 10 class, the object of the invention being to provide a toy comprising a ground or running wheel with a push bar or carrier, combined with a brake mechanism adapted to be actuated from a point in proximity to the 15 handle of the push bar whereby the child operating the device may occupy the brake mechanism to establish a braking action, thus adding interest to the manipulation of a toy of the class described.

20 The invention consists of the features of construction, combination and arrangement of parts hereinafter fully described and claimed, reference being had to the accompanying drawing in which—

25 Figure 1 is a perspective view of the device with the brake in normal position. Fig. 2 is a similar view of the device with the brake in applied position. Fig. 3 is a detail section on line 3—3 of Fig. 1.

30 Referring to the drawing, 1 designates a trundle wheel, which is suitably journaled upon one end of a push bar or carrier 2, provided at its opposite or free end with a suitable form of handle 3. In the use of 35 this device the operator grips the handle 3 in one end and holds the bar 2 elevated and exerts a forcing pressure thereon to force the wheel 1 forward, the wheel running upon the surface of the ground in advance 40 of the operator who walks or runs behind it.

In carrying my invention into practice, I provide a brake device comprising a brake shoe 4 arranged to engage the periphery of the wheel 1, and which is mounted upon one 45 end of a brake applying lever 5. This lever 5 extends vertically above and below the bar 2 and is pivotally mounted at an intermediate point upon the bar, as shown at 6. Similarly mounted upon the rear end of the 50 bar 2, adjacent to the handle 3, is a brake

actuating lever 7, which extends vertically above and below the bar and is pivotally mounted thereon, as indicated at 8. The upper end of this lever is provided with a suitable handle 9 while the lower end of 55 said lever is connected with the upper end of the lever 5 through the medium of lever mechanism comprising a power transmitting lever 10 pivotally mounted upon the bar, as indicated at 11, and having its lower and 60 upper ends respectively connected with the upper ends of the levers 5 and 7 by means of links 12 and 13, the construction being such that by moving the handle 9 rearwardly toward the handle 3 the levers will be moved 65 in a proper direction to throw the brake shoe 4 into engagement with the wheel 1, while a reverse movement of the handle 9 will move the levers to retract or withdraw the brake shoe from engagement with the 70 wheel.

It will thus be seen that I provide a trundle wheel device with a simple form of brake mechanism by means of which the operator of such device may throw the brake 75 mechanism into and out of action to control the running speed, and so as to simulate the braking action of a vehicle, thus adding zest and amusement to the manipulation of such devices. The form of lever mechanism 80 provided is applicable at a comparatively low cost and is adapted to establish a powerful braking action.

I claim:—

1. A toy comprising an actuating bar having a handle at one end thereof, a trundle wheel journaled upon the opposite end of the bar, a brake member supported by the bar in position to engage the trundle wheel, a brake operating lever mounted upon the 90 bar in proximity to the handle, and connections between said lever and the brake member for actuating the latter.

2. A toy comprising a trundle wheel, an actuating bar or lever, a brake shoe mounted upon the bar, and a system of levers for operating said shoe, arranged to be actuated from a point adjacent to the handle of the bar.

3. A toy comprising a trundle wheel, an 100

actuating bar or lever therefor, provided at its rear end with an operating handle, a lever pivotally mounted on the bar, a brake shoe carried by said lever, an operating lever 5 mounted upon the bar adjacent to the handle thereof, and link and lever connections

between said brake and actuating levers, whereby the brake shoe may be thrown into and out of action from a point in proximity 10 to the handle of the bar.

In testimony whereof I affix my signature.

WILLIAM DAVIS SMITH.
